UNITED STATES PATENT OFFICE

WALLACE O. GOULD, OF BRUNSWICK, MAINE

DESIGN FOR A CLOCK CASING

Application filed March 18, 1929. Serial No. 30,506. Term of patent 3½ years.

To all whom it may concern:

Be it known that I, WALLACE O. GOULD, a citizen of the United States, residing at Brunswick, in the county of Cumberland and State of Maine, have invented a new, original, and ornamental Design for a Clock Casting, of which the following is a specification, reference being had to the accompanying drawing, forming part thereof.

Fig. 1 is a front elevation of a clock casing, showing my new design, and
Fig. 2 is a plan view thereof.

I claim:

The ornamental design for a clock casing, as shown.

WALLACE O. GOULD.
